BOOM MOUNTING FOR MICROPHONES

Paul S. Veneklasen, Saugus, Mass., assignor to the United States of America, as represented by the Executive Secretary of the Office of Scientific Research and Development

Application April 26, 1945, Serial No. 590,411

1 Claim. (Cl. 179—156)

1

This invention relates to microphones and more especially to a boom mounting for supporting microphones such as a noise-cancelling type microphone in a speaking position.

Noise-cancelling microphones, also referred to as differential microphones, have been found to provide improved communication efficiency in extreme noise fields as compared with standard hand-held or throat microphones. However, the advantages of the noise-cancelling microphone are largely offset by difficulties resulting from the means of suspending it before the lips of the operator. The suspension means essentially consists of a strap arrangement or harness which is held against the face of the operator. The harness urges a frame member against the upper lip at either side of the nose. The frame supports the microphone in a position directly in front of the lips in a position which is recognized as being proper for efficient use of the microphone.

In actual use the harness may, under some conditions, cause skin irritation, and the frame may cause discomfort from excessive pressure against the upper lip. The microphone, when supported in this manner, may also become moved out of position under actual flying conditions, and this affects communication. There is also the problem of interference of the suspension means with other flying equipment such as oxygen masks, goggles, and the like.

An object of the invention therefore is to provide an improved means of suspending a noise-cancelling microphone before the lips of an operator and to devise a boom suspension which overcomes the difficulties above noted by avoiding all contact with the face and by providing for a greatly increased range of adjustability. Another object of the invention is to provide a simple, positive, efficient, and easily operated boom suspension for a microphone. Other objects will be apparent from the following description of the invention.

In the accompanying drawings:

Fig. 1 is a diagrammatic view illustrating the boom mounting of the invention in an operating position;

Fig. 2 is a plan view of the boom member and a microphone;

Fig. 3 is a view in side elevation of the boom mounting;

Fig. 4 is a cross section taken on the line 4—4 of Fig. 3;

Fig. 5 is a cross section taken on the line 5—5 of Fig. 3; and

2

Fig. 6 is a diagrammatic view illustrating a modification of the boom mounting.

The boom mounting of the invention is made up of a boom member, means for adjustably securing the boom member to a headset, and means for supporting a microphone in the boom member. In a preferred embodiment of the invention, I provide a boom formed of a spring steel wire bent upon itself in the manner shown. 5 Means for adjustably securing the boom to a headset and means for attaching a microphone to the boom have been provided, to cooperate with a boom of the wire type. It should be understood, however, that the invention is not limited to 10 the specific structure hereinafter described either with respect to the boom or its method of attachment to a headset or the means for supporting a microphone. Also the boom mounting is not limited to use with noise-cancelling microphones and may be employed with conventional 15 types.

In Fig. 1 I have diagrammatically illustrated the boom mounting of the invention in an operative position and attached to a headset of the 20 type in which a helmet 2 is fitted with an earphone socket 4 carrying an earphone 6. Secured to the socket member by some suitable means as rivets is a bracket 8 which may for example consist of a piece of sheet metal of substantially 25 U-shape (Fig. 1). At the lower side of the bracket is adjustably secured a suspension member 10 consisting of another thin piece of sheet metal which is rounded at its upper end and which flares downwardly and outwardly, terminating in a reversely bent portion to form a 30 clip 11, as may be better seen in Fig. 4. A rivet 12 is pivotally mounted through the bracket 8 and passes through the suspension 10 which is fixed thereto. Interposed between the head of 35 the rivet and the bracket 8 is a cupped washer 14 which tends to pinch the bracket against the suspension. The effect of this is to maintain 40 the suspension in a fixed position and a positive rotative force is required to turn the suspension member and rivet in the bracket. 45 16 denotes washers located at the side of the suspension member and 18 indicates a snap fastener also fixed at the outer end of the rivet (Figs. 3 and 4).

The clip portion 11 at the lower end of the 50 suspension member is formed with an opening 17 through which is slidably mounted a boom member 20 (Fig. 3). At the front end of the clip is provided a tab 22 which, together with a second tab member 24 on a clip 26 is also secured to the 55 boom 20, may be gripped between the thumb

and forefinger to slide the boom through the clip in a rearward direction. Movement of the boom forwardly may also be conveniently carried out by placing the thumb against the rear extremity of the boom and gripping the tab 22 with the forefinger. The slot in the clip portion 11 is of a size suitable for firmly gripping the boom and maintaining it in any position in which it may be disposed.

Also provided in the clip portion 11 is a spring tongue 28 formed with a tab 30, as shown in Figs. 3 and 4. The tongue normally assumes a depressed position, as illustrated in Fig. 2, so that it constitutes a stop against which the end of the boom may come to rest when advanced all the way ahead. The stop thus prevents accidental removal of the boom from the clip. Whenever it is desired to disengage the boom from the clip completely, the tab 30 and the tab 22 are grasped between thumb and forefinger, and forced toward one another. This causes the spring tongue to move outwardly away from the clip and the boom 20 may then be readily removed from the clip.

Boom 20 is preferably formed of a relatively stiff spring wire bent into a substantially rectangular shape, with the front end of the rectangle increasing in width and being offset to provide a noise-cancelling microphone support, as illustrated in Figs. 1, 2, and 3. A microphone 32 is adjustably secured in the boom by means of a flat spring 34 which is fastened to one side of the microphone and formed with curved edges which slidably engage over the boom member. Spaced rearwardly from the microphone 32 is a stop 36 fixed on the boom, to assist in positioning the microphone. By placing the thumb against the stop member 36 and the forefinger against the microphone, it is possible for the operator to move the microphone on the offset portion of the boom, and thus obtain a correct positioning of the microphone before the lips.

Electrical conductors 38 are connected at the lower side of the microphone as shown in Fig. 3, and slidably attached to the conductor cable is a snap fastener 40 adapted to engage with the snap fastener portion 18 already referred to as mounted on the suspension member 10. When the two fastener portions are interlocked in the manner illustrated in Fig. 1, a sudden pull on the cord 38 has little effect on the adjustment of the boom since the force is received on the axis of the rivet 12. The position of the wire or cord looped over the end of the boom 20 has been shown in the drawings for the purpose of more fully disclosing the clip construction. In actual use the cord is completely separated from the boom.

The boom mounting may be modified in various respects and may also be utilized with other types of equipment. For example, in Fig. 6 I have illustrated a sound-powered unit 44. This type of equipment is not furnished with a socket member but is customarily provided with a pivoted hanger 46 which extends below the receiver. In accordance with the invention, I attach to the member 46 a bracket 48 which may consist of a thin metal piece, tapered at its lower end. To the bracket the boom mounting structure already described, including the suspension member 10, is pivotally secured by some suitable means as a rivet transversely located therethrough. Various other changes and modifications may be employed. In place of the wire boom, sheet metal and other substances formed into a similar shape may be utilized. Also, changes in

the bracket and suspension members as well as the adjustment structures, may be resorted to.

In the actual operation of the boom mounting, a number of desirable adjustments are available, which are particularly important in flying. As noted in Fig. 1, the pivoted mounting of the suspension member on the bracket permits rotation of the boom mounting so that the boom and microphone assembly may be moved away from a position in front of the face into two standby positions. One of the standby positions consists in rotating the boom and microphone upwardly and allowing it to lie against the helmet 2, as has been indicated by means of the dotted line showing. The second standby position is arrived at by pivoting the boom and microphone assembly downwardly away from the face into a position in which the boom rests upon the chest of the operator, as has also been indicated by the dotted line showing of Fig. 1. In providing for these adjustments, it is pointed out that the cupped washer means tends to hold the boom and microphone in a relatively firm position wherever desired, thus insuring stability under various conditions. This result is obtained while permitting the boom member to be readily swung in either one of the standby positions.

A second adjustment available in using the boom mounting is obtained by the slideable mounting of the boom member in the clip 11, as has already been pointed out. The adjustability provided here permits movement of the boom forwardly and rearwardly to accommodate different head sizes and thus furnish an accurate means for positioning the microphone at the precise point before the lips required for good communication. The ability to retract the boom in the clip is also made use of in swinging the boom into standby positions. For example, in placing the boom in the raised position noted in Fig. 1, it may also be desired to slide the boom rearwardly a slight distance.

Still a third change may be carried out by the slideable arrangement of the boom in the clip, which consists in completely disengaging the boom from the clip member in the manner above described, and yet preventing accidental removal at such times as this is not desired. It should also be observed that the adjustment of the boom for purposes of positioning this member before the lips can be carried out with one hand, thus leaving the other hand free for different operations. In the case of complete disengagement of the boom, two hands are required but it is a very quick and easily carried out operation.

A fourth adjustment is provided by the slideable mounting of the microphone and the offset shape of the front end of the boom. This adjustment can be carried out in conjunction with rotation of the boom on the bracket to obtain further desired changes in positioning the microphone before the lips. The means of attaching the microphone are also convenient for replacement purposes.

In comparison with other noise-cancelling microphones supporting means, the structure of the invention eliminates all contact of supporting parts with the face, and in particular the sensitive upper lip. Consequently, all possibility of discomfort is avoided. Accidental movement of the microphone into a faulty position is prevented to a large extent since a more stable supporting means is present. The arrangement of the boom mounting at the side of the face and in front of the lips is particularly desirable in that it

avoids interference with other equipment such as goggles or oxygen masks. Finally, it is pointed out that a sudden jerk or pull on the conductor cable will not easily disturb the position of the microphone since the force is taken up on the axis of the rivet members.

Having thus described my invention, what I claim is:

An article of the character described comprising a bracket member adapted to be secured to a headset, a suspension member pivotally secured to the lower side of the bracket, means for retarding pivotal movement of the suspension member relative to the bracket, a clip portion formed at the under side of the suspension member and having a slot provided therein, a boom member slidably received in the said slot, tab means located on the boom for advancing and retracting the boom in the said clip portion, stop means for preventing removal of the boom from the clip, said boom consisting of a stiff wire member bent into rectangular shape and adapted to as-

sume a position in front of the mount, a noise-cancelling microphone slidably supported in the front end of the boom at the inwardly turned portion, a stop member fixed to the boom in spaced relation to the microphone, electrical conductor wires attached to the microphone, a snap fastener adjustably secured to the conductor wires and said snap fastener adapted to be connected to the bracket independently of movement of the suspension member.
